UNITED STATES PATENT OFFICE

110,641

DESIGN FOR A TEXTILE FABRIC

David Hess, Brooklyn, N. Y.

Application April 21, 1938, Serial No. 76,670

Term of patent 14 years

To all whom it may concern:

Be it known that I, David Hess, a citizen of the United States, residing in Brooklyn, in Kings County and in the State of New York, have invented a new, original, and ornamental Design for a Textile Fabric, of which the following is a specification, reference being had to the accompanying drawing, forming part thereof.

The figure is a plan view of a piece of textile fabric showing my new design.

The characteristic feature of the present de-

sign resides in the grosgrain fabric having leather strips of uniform width replacing the warp at intervals transversely of the fabric, the intervals being substantially equal to the width of the strips, the cross threads covering the strips at equally and relatively widely spaced intervals, thereby leaving the strips substantially exposed.

I claim:

The ornamental design for a textile fabric, substantially as shown and described.

DAVID HESS.
